FIG. 3

FIG. 1

FIG. 2

FIG. 4

FIGURE 1 is a front elevational view of a combined tire tread depth gauge and marker showing my new design.

FIGURE 2 is a side elevational view thereof.

FIGURE 3 is a top plan view thereof.

FIGURE 4 is a bottom plan view thereof.

The rear of the circular dial portion of the gauge is substantially plain in appearance.

The broken line portion indicating chalk or crayon is depicted for illustrative purposes only.

I claim:

The ornamental design for a combined tire tread depth gauge and marker, substantially as shown and described.
